UNITED STATES PATENT OFFICE.

JOSEPH A. PRARAY AND HARRY S. GREENE, OF WOONSOCKET, RHODE ISLAND, ASSIGNEES TO WOONSOCKET NAPPING MACHINERY CO., OF WOONSOCKET, RHODE ISLAND.

NAPPING-MACHINE DRUM.

1,016,174.

Specification of Letters Patent.

Patented Jan. 30, 1912.

Application filed July 14, 1910. Serial No. 571,963.

To all whom it may concern:

Be it known that we, JOSEPH A. PRARAY and HARRY S. GREENE, citizens of the United States, residing at Woonsocket, in

5 the county of Providence and State of Rhode Island, have invented new and useful Improvements in Napping-Machine Drums, of which the following is a specification.

10 Our invention relates to drums such as are employed in planetary napping machines; and it has for its object to provide for the mounting of the napping rolls between the heads of the drum in such manner 15 that the rolls are supported at points intermediate the drum heads by anti-friction means, this being materially advantageous inasmuch as when mounted on anti-friction means at points intermediate the drum 20 heads, the napping rolls are adapted to be rotated about their axes by but little power, and without subjecting the rolls or the connections between the same and the drum heads to strain, and being also advantageous 25 inasmuch as it obviates the necessity of providing accommodations in the drum heads for the anti-friction means.

The invention will be best understood by reference to the following description when 30 taken in connection with the accompanying illustration of certain specific embodiments thereof, while its scope will be more particularly pointed out in the appended claim.

35 In the drawings which are hereby made a part hereof: Figure 1 is a section, taken in the plane indicated by the line 1—1 of Fig. 2 and illustrating the preferred embodiment of our invention. Fig. 2 shows the bearing in end elevation. Figs. 3 and 40 4 are cross-sections taken in the planes indicated by the lines 3—3 and 4—4, respectively, of Fig. 1. Figs. 5 and 6 are sectional views of modifications hereinafter specifically referred to.

45 Referring by letter to the said drawings, and more particularly to Figs. 1 to 4 thereof: A is one head of the revoluble drum comprised in the conventional planetary napping machine.

50 B is a spindle connected with and extending laterally inward from the head A, and C is a bracket fixed with respect to the head A, and which carries the spindle B in such manner that the latter is held against rotation.

55 The spindle B is provided at a and b

with abutments against which are arranged cones c and d, respectively, and in races formed between the said cones and a shell e are arranged the balls f which constitute the type of anti-friction devices we prefer to employ. The inner cone d is secured by a nut and a washer or other suitable means on the spindle B, and the shell e is snugly arranged and preferably, though not necessarily, fixed in the napping roll D which is 60 tubular, as illustrated.

Suitably fixed to and surrounding the portion of the tubular roll D which surrounds the anti-friction support described is a collar E designed for engagement with 70 the belt (not shown) through the medium of which the napping roll D is rotated about its axis incidental to the rotation of the napping drum.

It will be gathered from the foregoing 75 that the napping roll D serves to inclose and protect its anti-friction bearing, and that very little power applied through the collar E is required to rotate the roll D.

It will also be gathered that the bracket 80 C is adapted to be expeditiously and easily attached to the perimeter of a drum head, and that the spindle B and the anti-friction means interposed between the spindle and the napping roll D obviate the necessity of 85 providing the head with means to receive the anti-friction support of the roll.

In Fig. 5 is shown a comparatively simple and cheap construction designed more particularly for embodiment in small machines. 90 The said construction differs from that shown in Figs. 1-4 in that but one cone c⁵ is employed on the spindle B⁵, the shell e⁵ is shaped accordingly.

In the modified construction of Fig. 6, 95 the spindle B⁶ is provided with a casing portion e⁶ which surrounds the end portion of the napping roll D⁶ and serves in combination with the said roll and the collar E⁶ thereon to form races for the two series of 100 anti-friction devices f⁶, preferably balls, interposed between the casing and the roll.

It will be noted that in all of the illustrated embodiments of our invention, the anti-friction bearing is applied either with 105 in or without the napping roll instead of in or upon the head of the napping drum as is the ordinary practice.

While we have illustrated the mounting of but one end of the napping roll, we 110

would have it understood that both ends of the roll will be mounted in the same manner.

Having described our invention, what we claim and desire to secure by Letters-Patent, is:

The herein described planetary napping machine drum, consisting essentially of a revolute head, a spindle fixed to and extending laterally inward from the head, a napping roll arranged entirely at the inner side of the head and supported by and arranged and adapted to turn concentrically to the spindle and provided with means as

a collar for engagement with a band that is 15 adapted to turn the roll about its axis incident to revolution of the drum head, and anti-friction means interposed between the spindle and the roll.

In testimony whereof we have hereunto set our hands in presence of two subscribing witnesses.

JOSEPH A. PRARAY.
HARRY S. GREENE.
